RAILWAY CAR

Walter B. Dean, Paris, France, and William H. Chandlee, Jr., Southampton, Pa., assignors to The Budd Company, Philadelphia, Pa., a corporation of Pennsylvania

Application April 4, 1950, Serial No. 8,972

Term of patent 14 years

(Cl. D66—1)

To all whom it may concern:

Be it known that we, Walter B. Dean and William H. Chandlee, Jr., citizens of the United States, and residents, respectively, of Paris, France, and Southampton, State of Pennsylvania, U. S. A., have invented a new, original, and ornamental Design for a Railway Car, of which the following is a specification, reference being made to the accompanying drawing, forming a part thereof.

In the drawing:

Figure 1 is a side elevational view of a railway car, showing our design;

Figure 2 is a three-quarter perspective view of the railway car, as seen from one end of the car; the view being on an enlarged scale.

The opposite side of the railway car design from that shown in the figures is the same as the side shown.

The characteristic features of our design reside in the portions shown by means of full lines in the drawing.

We claim:

The ornamental design for a railway car, substantially as shown and described.

WALTER B. DEAN.

WILLIAM H. CHANDLEE, JR.
